UNITED STATES PATENT OFFICE.

FREDERIC G. NICOLAUS, OF CLEVELAND, OHIO, ASSIGNOR TO AMERICAN STOVE COMPANY, OF ST. LOUIS, MISSOURI, A CORPORATION OF NEW JERSEY.

STOVE-DOOR HINGE.

1,159,255.

Specification of Letters Patent.

Patented Nov. 2, 1915.

Application filed July 13, 1915. Serial No. 39,633.

To all whom it may concern:

Be it known that I, FREDERIC G. NICOLAUS, a citizen of the United States, residing at Cleveland, in the county of Cuyahoga and 5 State of Ohio, have invented certain new and useful Improvements in Stove-Door Hinges, of which the following is a specification, reference being had therein to the accompanying drawing.

10 My invention relates to improvements in stove door hinges.

The object of my invention is to provide a hinge of this character which is readily secured to the door-frame by means of a single 15 bolt and which obviates the necessity of drilling holes in the door-frame for securing the hinge thereto and supporting means whereby the door is held in its adjusted position.

20 Another object of my invention is to provide a stove door hinge of this character in which the wearing parts can be readily removed and replaced, and at the same time providing a simple, cheap and effective 25 hinge having certain details of structure and combination of parts hereinafter more fully set forth.

In the accompanying drawings, Figure 1 is a perspective view of my improved hinge 30 showing it applied to the drop door of a gas range oven. Fig. 2 is a horizontal sectional view taken on the line 2—2 of Fig. 1. Fig. 3 is an enlarged perspective view of the hinge and its several parts showing them in 35 their disassembled relation. Fig. 4 is a vertical sectional view of one of the hinged sections showing the door in the open position.

Referring now to the drawings, 1 represents the front frame of the oven which is 40 preferably made of angle iron having a short leg 2 and a long leg 3 shown in Fig. 3 of the drawings. The short leg 2 of the angle iron has a cut away portion 4 while the long leg has a cut-away portion 5 communicating therewith. The end of the cut-away portion 5 is provided with a cut-away portion 6 having its outer end curved for the purpose hereinafter more fully described.

50 While I have described but one of the openings in the angle-iron it will be understood that there are two arranged the proper

distance apart, and the second opening has the cut-away portion 6 arranged on the opposite side from that shown in Fig. 4 of 55 the drawings so that the thrust of the pintles is taken up by the bearings arranged therein.

The door-frame 7 is made of any desired form and is provided at its lower end with 60 the downwardly extending lugs 8 and 9 which may be cast integral therewith or made in any other desired manner. These lugs are preferably of an enlarged cylindrical form as indicated at 10 having on 65 opposite sides the hinge pintles 11 which as shown in Fig. 3, of the drawings, are eccentrically arranged. The door-frame 7 is cut-away as indicated at 11' for the purpose of providing room for the enlarged heads of 70 the combined securing bolts and pintle bearings to be later described. The cylindrical members 10 are provided with an extension 12 having the rounded face 13 and the flat face 14 clearly shown in Fig. 4 of the drawings.

The pintle bearings consist of a large, flat head 15 which have one side cut-away which is indicated at 16, which allows for the cylindrical member 10 to bring it in close to 80 the same. Carried by the enlarged head 15 is an enlarged body portion 17 which is of a size to snugly fit the cut-away portion 6 of the leg 3 of the angle-iron and whereby the same is prevented from turning and is provided with a horizontally disposed opening 18 adapted to fit the pintles 11, as clearly shown in Fig. 2 of the drawings. Extending outwardly from the body portion 17 is a 85 screw-threaded extension 19. The head 15 of the pintle bearing rests against the outer face of the leg 3 and prevents the inward movement thereof through the cut-away portion 6 in the angle-iron. Surrounding the screw-threaded extension 19 of the pintle bearing is a saucer-shaped member 20 which has one side cut-away as indicated at 21, which allows the free movement of the cylindrical member 10. Screwed upon the extreme outer end of the screw-threaded extension 19 is a nut 22 which clamps the saucer-shaped member 20 against the inner face of the angle-iron and allows for the 95 enlarged body portion 17 so that ample ma- 100

terial is provided for the bearing for the pintle. The inner face of the leg 3 of the angle-iron has secured thereto by means of a bolt 23, a member 24 which extends outwardly and normally bears against the periphery of the cylindrical members 10, carried by the door. The rounded face 13 of the cylindrical member is adapted to bear against the inner face of the member 24, and the pintles 11 being eccentrically arranged, it will be seen that when the stove door is swung outwardly, this rounded face engages the inner face of the member 24 and springs the same outwardly, whereby the door will be frictionally held in its adjusted position. In order to limit the movement of the door upon a horizontal plane, the cylindrical members are provided with extensions 25 which engage the lower face of the leg 2 of the angle iron, as clearly shown in Fig. 4 of the drawings.

While I have shown and described this specific form of hinge and friction holding means, it will be understood that the same could be varied without departing from my invention.

Having thus fully described my invention what I claim and desire to secure by Letters Patent is:

30 1. The combination with a stationary member, of a movable member having a pintle, and a pintle bearing having means for attachment to the said stationary member, and friction means for holding the movable member in its adjusted position.

35 2. The combination with a stationary member having a cut-away portion, of a movable member having a pintle carrying member entering said cut-away portion, means secured within the cut-away portion and forming a bearing for said pintle, and friction means for engaging the movable member and holding it in its adjusted position.

40 3. The combination with a member having a cut-away portion, of a movable member having a pintle carrying member entering said cut-away portion, a locking bolt forming a bearing for said pintle, and means for engaging the movable member for holding it in its adjusted position.

45 4. The combination with a stationary member having cut-away portions, of a movable member having pintle carrying members entering said cut-away portions, locking bolts forming bearings for said pintles, and means carried by the stationary member for engaging the pintle carrying members and holding the movable member in its adjusted position.

50 5. The combination with a stationary member having cut-away portions, of a movable member having pintle carrying members, entering said cut-away portions, locking bolts forming bearings for said pintles,

and a member secured to the stationary member and extending outwardly and engaging the pintle carrying members for holding the movable member in its adjusted position.

6. The combination with a stove-frame having cut-away portions, of a door having eccentrically arranged pintle carrying members entering said cut-away portions, locking bolts forming bearings for said pintles, and a member secured to the stove-frame between the pintle carrying members and adapted to engage the same for holding the door in its adjusted position.

7. The combination with a stove-frame having cut-away portions, a stove-door pintle carrying members carried by the door and entering said cut-away portions, locking bolts forming bearings for said pintles, a member secured to the frame between the pintle carrying members, and adapted to engage the same for holding the door in its adjusted position.

8. The combination with a stove-frame having cut-away portions, of a door, pintle carrying members entering said cut-away portions, pintles eccentrically carried by said members, means secured within the cut-away portions and forming bearings for said pintles, a member secured to the frame intermediate the cut-away portions and having outwardly extending arms engaging the periphery of the eccentrically arranged pintle carrying members, whereby the door is held in its adjusted position.

9. The combination with a stove-frame having cut-away portions, of a door, members carried by said door and entering the cut-away portions, pintles eccentrically carried by the said members, locking bolts forming bearings for said pintles and secured within the cut-away portions, an elongated plate secured to the frame intermediate the cut-away portion, and having outwardly extending arms engaging the periphery of the pintle carrying members, and outwardly extending lugs carried by the pintle carrying members, and adapted to engage the frame for limiting the downward movement of the door.

10. The combination with a stationary member having a cut-away portion, of a movable member having a pintle carrying member entering said cut-away portion, locking bolts secured within the cut-away portion and forming bearings for the said pintles intermediate the head and nut, and means for engaging the movable member for holding it in its adjusted position.

11. The combination with a stationary member having cut-away portions, of a movable member having pintle carrying members entering said cut-away portions, locking bolts secured within the cut-away portion, and having bearings intermediate the head

and the locking nut thereof forming bearings for the pintle, and a member secured to the said stationary member and extending outwardly and engaging the pintle carrying 5 members for holding the movable member in its adjusted position.

In testimony whereof I hereunto affix my signature in the presence of two witnesses.

FREDERIC G. NICOLAUS.
